DESIGN FOR A PNEUMATIC TIRE

Harry S. Curtiss, Eau Claire, Wis., assignor to
Gillette Rubber Company, Eau Claire, Wis., a
corporation of Wisconsin

Application May 27, 1936, Serial No. 62,868

Term of patent 14 years

To all whom it may concern:

Be it known that I, Harry S. Curtiss, a citizen
of the United States of America, residing at Eau
Claire, county of Eau Claire, and State of Wis-
consin, have invented a new, original, and orna-
mental Design for Pneumatic Tires, of which the
following is a specification, reference being had
to the accompanying drawing, forming part
thereof, wherein:—

Fig. 1 is a plan view of a portion of a pneumatic
tire embodying the ornamental design;

Fig. 2 is a side view thereof; and

Fig. 3 is a cross sectional view thereof taken
along the section line 3—3 of Fig. 1.

I claim:—

The ornamental design for a pneumatic tire, as
shown.

Signed at Eau Claire, county of Eau Claire, and
State of Wisconsin, this 18th day of May, 1936.

HARRY S. CURTISS.
